Otho O'Sullivan,

By his attorney,
Mark J. Penney

UNITED STATES PATENT OFFICE.

OTHO O'SULLIVAN, OF WILLIMANTIC, CONNECTICUT.

THREAD GUIDE FOR SPINNING MACHINES.

Application filed November 24, 1923. Serial No. 676,752.

REISSUED

To all whom it may concern:

Be it known that I, OTHO O'SULLIVAN, citizen of the United States, and resident of Willimantic, in the county of Windham and State of Connecticut, have invented certain new and useful Improvements in Thread Guides for Spinning Machines, of which the following is a specification.

This invention has reference to guides for winding or spinning machines, where a thread is drawn from one spool or bobbin and wound upon another spool.

The object of the present invention is to provide a thread guide that will have its portion adapted to engage a thread of considerable extent or area, and which member can be readily shifted or adjusted whereby a considerable number of different surfaces can be brought to position for engagement with the thread, and by a comparatively small and simple adjustment on the support for the guide member.

A further object of the invention is to provide a special guide arm to prevent the thread movement away from its desired engaging position, and which member is also made adjustable to be shifted corresponding with the shifting movement of the thread engaging portion.

In the accompanying drawing showing one embodiment of my invention, Figure 1 is a side elevation of the device.

Fig. 2 is a longitudinal section.

Fig. 3 is a transverse section.

Fig. 4 is a similar view showing wear in the disc by the thread.

Fig. 5 shows the device with the guide or thread retainer, in side elevation.

Fig. 6 is a transverse section through the device as shown in Fig. 5.

In the use of such devices as these, especially where the member that engages the thread is formed of a non-metallic substance such as porcelain, it is found that the friction of the thread passing against the guide surface will soon wear away such surface and provide a groove which becomes injurious to the thread. It then becomes necessary to provide a fresh unworn surface for the thread.

In the present invention I provide a thread guide which has a large number of available thread engaging portions, and the guide member itself is readily adjustable on its support to bring different portions of such member into the path of movement of the thread; and which portion

will be brought to the same path of movement by such adjustment, and without shifting the supporting member.

In the arrangement shown herein I provide a support in the form of a disc or spool 7 that is adjustably carried by a supporting member in the form of a rod or stem 8. The disc is shown as provided with a comparatively deep annular groove 9. The disc is provided with a bore 10, into which projects the end portion 12 of the stem, that is bent to extend at a right angle to the stem 8. This bent portion is passed through the bore of the spool, and the extremity is provided with suitable fastening means, such as a nut 13 engaging the screw thread extremity 14 of the stem. It will be understood that when this nut is tightened against the side face 15 of the spool, the latter will be pressed on the bent portion of the stem until the opposite face 15 of the spool will engage the stem 8.

Upon loosening the nut 13 the spool can obviously be turned on the bent stem and a different portion of the groove 9 will be brought to the path of movement of the thread 6, as indicated in Figs. 3 and 4, where as shown in Fig. 4 the shaded portion 4 represents a worn portion of the spool groove, that by slightly turning the spool will cause a fresh unworn part to engage the thread 6, and the nut 13 is again tightened to secure the spool in this position.

While such an arrangement would provide a considerable number of adjustments for the spool on the stem, I preferably provide abutment portions on the spool for engagement with the stem. As shown the spool on the side 15 is provided with a series of radial grooves 16, of a size to fit the stem 8 that is brought to register therewith as indicated in Fig. 2. As shown I provide eight of these radial grooves that will give eight different positions of adjustment for the spool on the stem and which will be equally spaced apart. When any one place becomes worn by the thread 6 the nut 13 is loosened and the spool slightly moved to bring the groove away from the stem 8, and then the spool is turned to bring an adjacent groove 16 opposite the stem, when the nut is again tightened. Each fresh surface of the spool groove is in the same position relative to the path of the thread 6.

It is further desirable to provide a kind of guide or retainer for the thread to pre-

vent its getting out of the spool groove. In Figs. 5 and 6 I show a guide formed by a rod 20 having a loop 21 adapted to be clamped between the nut 13 and the adjacent 5 face of the spool, as clearly shown in Fig. 6. The end portion 22 of the guide extends transversely across the plane of the spool, and also that of the stem 8, as indicated in Fig. 6. This member and the stem 8 will 10 prevent the thread from moving out of the groove. When the nut is loosened to adjust the spool on the stem, the guide arm 22 can also be shifted to retain it in proximity to the stem. The side 15 of the spool may also 15 be provided with a series of radial grooves 23 arranged to engage the stem 20, and which grooves are arranged similar to the grooves 16 on the opposite side. When the spool is shifted on the stem to engage another 20 groove with the stem, the guide arm is also shifted in a similar manner, to engage the next groove, and will thus maintain its position relative to the supporting stem 8.

It will be noted, by referring to Fig. 5, 25 that the retainer 20 is angularly inclined to the supporting stem 8 relatively, so that the extension 22 thereof overlies the supporting stem 8 thereby permitting the ready introduction of thread therein by a sidewise motion. In order to accommodate the desired 30 angular relation of the retainer to the supporting stem in the grooves 16 on opposite sides of the guide 7 the said grooves are spaced in staggered relation to each other on 35 opposite sides and they therefore maintain the retainer and support rod 8 in the desired relation.

What I claim is:

1. A thread guide, comprising a disc provided with a comparatively deep annular groove for frictionally engaging the thread, the disc having an axial bore, a holder for the disc comprising a rod bent to extend transversely at its end portion and adapted 40 to engage the disc bore, securing means on the free projecting end of the rod bent portion, the disc having a plurality of means for engagement with the stem on one side face, whereby the fastening means will 45 clamp the stem at such portions to hold the disc against turning, and on loosening such securing means the disc can be shifted on the stem for engagement with other said engaging portions and clamped in such adjusted 50 positions by said means, and a thread guide held by said stem retaining means on the opposite face of the disc in adjusted positions, said guide having an arm deflected across the plane of the disc and that of the 55 stem.

2. A thread guide, comprising a disc provided with a comparatively deep annular groove for frictionally engaging the thread, the disc having an axial bore, a holder for 60 the disc comprising a rod bent to extend

transversely at its end portion and adapted to engage the disc bore, securing means on the free projecting end of the rod bent portion, the disc having a plurality of means for engagement with the stem on one side 70 face, whereby the fastening means will clamp the stem at such portions to hold the disc against turning, and on loosening such securing means the disc can be shifted on the stem for engagement with other said engaging portions and clamped in such adjusted 75 positions by said means, and a thread guide held by said stem retaining means on the opposite face of the disc in adjusted positions, said guide having an arm deflected across 80 the plane of the disc and that of the stem, the disc having abutment portions on said face for engagement with the guide to permit adjustment thereof to correspond with 85 adjustment of the stem.

3. A thread guide, comprising a disc of porcelain or similar material provided with a comparatively deep annular groove for the thread, the disc having an axial bore, a holder for the disc comprising a rod bent 90 to extend transversely at its end portion and adapted to engage the disc bore, securing means on the free projecting end of the rod bent portion, the disc having abutment portions for engagement with the stem on one 95 side face, whereby the securing means will clamp the stem at such portion to hold the disc against turning, and on loosening such securing means the disc can be shifted on the stem for engagement with other of said 100 abutment portions and clamped in such adjusted positions by said securing means, and a thread guide held by securing means in adjusted 105 positions, to permit adjustment thereof to correspond with adjustment of the stem.

4. A thread guide, comprising a disc of porcelain or similar material provided with a comparatively deep annular groove for the thread, a holder for the disc, securing 110 means on the holder, the disc having abutment portions for engagement with the holder on one side face, whereby the securing means will clamp the holder to hold the disc against turning, and on loosening such 115 securing means the disc can be shifted for engagement with other of said abutment portions and clamped in such adjusted positions by said securing means, and a thread 120 guide held by said securing means on the opposite face of the disc in adjusted positions, the said guide having an arm deflected across the plane of the disc and that of the stem.

5. A thread guide, comprising a disc of porcelain or similar material provided with a comparatively deep annular groove for the thread, a holder for the disc, securing means on the holder, the disc having abutment 125 portions for engagement with the holder on 130

- one side face, whereby the securing means will clamp the holder to hold the disc against turning and on loosening such securing means the disc can be shifted for engagement with other of said abutment portions and clamped in such adjusted positions by said securing means, and a thread guide held by said securing means on the opposite face of the disc in adjusted positions, said guide having an arm deflected across the plane of the disc and that of the stem, the disc having abutment portions on said face for engagement with the guide to permit adjustment thereof to correspond with adjustment of the stem.
6. A thread guide, comprising a disc of porcelain or similar material provided with a comparatively deep annular groove for the thread, the disc having an axial bore, a holder for the disc comprising a rod bent to extend transversely at its end portion and adapted to engage the disc bore, securing means on the free projecting end of the rod bent portion, whereby the securing means will clamp the stem on one side face to hold the disc against turning, and on loosening such securing means the disc can be shifted on the stem and clamped in such adjusted positions by said securing means, and a thread guide held by securing means in adjusted positions.
7. A thread guide of the class described, comprising a spool of vitreous material having means for receiving and lockably indexing thereto a support rod through one side thereof; and means on the opposite side of said spool for lockably indexing a thread retainer in angular indexed relation to said support rod.
8. A thread guide of the class described, comprising a vitreous grooved body having a rod supporting means thereon; and a plurality of radial grooves on opposite sides thereof; one set of grooves on one side of said guide being located in staggered relation to the corresponding grooves on the opposite side thereof.

Signed at Willimantic in the county of Windham and State of Connecticut this 19th day of November A. D. 1923.

OTHO O'SULLIVAN.
